UNITED STATES PATENT OFFICE.

ROBERT R. MARSH, OF DETROIT, MICHIGAN.

DESIGN FOR A REVOLVING PICTURE-CASE.

Specification forming part of Design No. 5,827, dated April 30, 1872.

Specification for and describing a Design for a Revolving Picture-Stand for Center-Tables, invented by ROBERT R. MARSH, of Detroit, in the county of Wayne and State of Michigan.

The nature of my design is fully shown in the accompanying photographic illustration, to which reference is made.

My picture-stand is in the general form of a hexagonal (or octagonal) pyramidal monument, constructed chiefly of hard wood, appropriately ornamented by carving, tracery, and gilding.

The base is supported by metallic feet at the lower ends of the corner pilasters, resting on the center-table, and each panel of the base has an oval opening cut in it to receive a small oil-painting, A, slipped in through a slot at the top, behind the panel, before the next sec-

tion is added. The base carries a central vertical spindle, (not seen,) around which revolves the upper part of the stand, consisting of paneled sections, in each panel of which an oval opening is cut, behind which are inserted photographic portraits in the manner already described. The portraits of the lower section are known as "imperial cabinets," the next above as "cabinets," and those of the upper section as "cartes," in designating their respective sizes, the upper section being surmounted by a vase or urn as a finial ornament.

What I claim as my invention is—

A design for a revolving picture-stand, substantially as described and shown.

R. R. MARSH.
